UNITED STATES PATENT OFFICE.

PHILIP J. HARRAH, OF BLOOMFIELD, INDIANA.

DESIGN FOR A HOLDER FOR FIRE-KINDLERS.

SPECIFICATION forming part of Design No. 23,355, dated June 12, 1894.

Application filed April 25, 1894. Serial No. 509,026. Term of patent 3½ years.

To all whom it may concern:

Be it known that I, PHILIP J. HARRAH, of Bloomfield, in the county of Greene and State of Indiana, have invented and produced a new 5 and original Design for Kindling Compounds and Holders Therefor; and I do hereby declare the following to be a full, clear, and exact description of the invention, such as will enable others skilled in the art to which it appertains to make and use the same.

The design for my fire-kindler holder comprises for its characteristic features a straight body A of elongated form, having a circular or ring-shaped extremity a at one end and a 15 skeletonized oval-shaped holder a' at the

other. This skeletonized holder a' consists of four arcs springing from the body and passing over, in oval form, to a union at the extreme tip a².

I claim—

The design for a fire-kindler holder, substantially as shown and described.

In testimony whereof I have signed this specification in the presence of two subscribing witnesses.

PHILIP J. HARRAH.
